UNITED STATES PATENT OFFICE.

JAMES A. ST. JOHN, OF NILES, OHIO.

FEED-BAG.

1,112,941.

Specification of Letters Patent.

Patented Oct. 6, 1914.

Application filed April 17, 1912. Serial No. 691,277.

To all whom it may concern:

Be it known that I, JAMES A. ST. JOHN, a citizen of the United States of America, residing at Niles, in the county of Trumbull and State of Ohio, have invented certain new and useful Improvements in Feed-Bags, of which the following is a specification, reference being had therein to the accompanying drawing.

10 This invention relates to feed bags, and the primary object of my invention is the provision of simple and effective means, as hereinafter set forth, for insuring perfect ventilation of the feed bag and the obtaining 15 of feed by a horse as the feed is consumed.

Another object of this invention is to provide an adjustable halter for supporting a feed bag and a feed bag with a telescopic 20 or flexible casing that prevents the contents of the bag from being wasted by the movement of a horse's head.

A further object of this invention is to accomplish the above results by a mechanical 25 construction that is durable, inexpensive to manufacture and highly efficient for the purposes for which it is intended.

With the above and other objects in view, the invention resides in the novel construction, 30 combination and arrangement of parts to be hereinafter specifically described and then claimed.

Reference will now be had to the drawing, wherein like numerals denote corresponding 35 parts throughout the several views, in which—

Figure 1 is a side elevation of the feed bag as applied to a horse's head, Fig. 2 is an enlarged vertical sectional view of the 40 feed bag and the halter therefor, Fig. 3 is a perspective view of the regulating cord, Fig. 4 is a front elevation of a portion of the feed bag, and Fig. 5 is a cross sectional view of a portion of the feed bag.

45 A feed bag in accordance with this invention comprises a pan or receptacle 1 and riveted or otherwise connected, as at 2 to the upper edges of the receptacle 1 is a band 3 that is employed for holding the lower edges 50 of a flexible casing 4 in engagement with the receptacle 1. The upper edges of the casing 4 are provided with a case 5 in which is located a ring 6. Connected to the upper edge of the casing 4 are equally spaced hangers 7 and loosely connected to said hangers by rings 8 are back straps 9 and front

straps 10. These straps are connected to side rings 11 and the side rings 11 are connected by a nose strap 12 and a head strap 13. The straps 9, 10, 11 and 13 are all adjustable and said straps constitute a halter that can be adjusted to fit upon horse heads of various sizes. The straps of the halter are equipped with buckles or slip plates 14 that permit of said straps being easily and 60 quickly lengthened or shortened. 65

Secured to the bottom of the receptacle 1 by metallic straps 15 or other fastening means is an eye 16 and extending through said eye is a regulating cord or rope 17. 70 The cord extends upwardly through guide straps 18 at diametrically opposite sides of said receptacle, the guide straps 18 being secured to the band 3. The cord extends over small pulleys 19 suspended from the side 75 rings 11, and the ends of the cord are tied to form a loop 20, as best shown in Fig. 3. The ends of the cord 17 are also connected by straps 21.

As illustrated in Fig. 1, the upper ends of 80 the cord 17 can be placed over the hames of a collar or even carried rearwardly to the saddle or to the backing strap of a harness. The ends of the cord 17 are movable over the 85 small pulleys 19 and it is obvious that when a horse's head is lowered that the pan or receptacle 1 will be elevated. As feed is consumed by a horse, it is natural that the head be gradually lowered, consequently the horse will at all times completely empty the feed 90 bag. It will also be noted by observing Fig. 1 that the feed bag is properly positioned whereby air can enter the upper end thereof and insure thorough ventilation of the 95 feed bag during the feeding operation.

By reference to Figs. 1 and 2 of the drawing it will be observed that a martingale 16^a can be attached to the eye 16 to prevent a horse from elevating the feed bag to the extent that the contents will be spilled. 100

It is thought that the operation and utility of the feed bag will be apparent without further description, and while in the drawing there is illustrated a preferred embodiment of the invention, it is to be understood 105 that the structural elements are susceptible to such variations and modifications as fall within the scope of the appended claim.

What I claim is:—

A feed bag comprising a rigid imperforate cylindrical receptacle having a flat bottom riveted thereto and adapted to contain

a quantity of feed, a band secured to the top of said receptacle, an annular flexible casing extending over the periphery of the said receptacle and secured to the lower end of said band, a stiffening ring for the upper end of said casing, diametrically opposed guide straps projecting laterally from said band, adjustable hangers connected to said ring and adapted to be attached to a halter, pulleys adapted to be suspended from the halter, an eye secured to the bottom of the receptacle, flexible members extending

through said eye and up through the guide straps and over said pulleys for elevating the receptacle, and a member secured to said eye for limiting upward movement of said receptacle. 15

In testimony whereof I affix my signature in the presence of two witnesses.

JAMES A. ST. JOHN.
